Primary Examiner—Ted Shooman*Assistant Examiner*—Carol Rademaker*Attorney, Agent, or Firm*—Marshall, O'Toole, Gerstein,
Murray & Borun[57] **CLAIM**

The ornamental design for a box for a book, as shown and described.

DESCRIPTION

FIG. 1 is a front elevational view of a box for a book in accordance with the present invention;

FIG. 2 is a rear elevational view of the box for a book of FIG. 1;

FIG. 3 is a right side elevational view of the box for a book of FIG. 1;

FIG. 4 is a left side elevational view of the box for a book of FIG. 1;

FIG. 5 is a bottom plan view of the box for a book of FIG. 1, the top plan view being a mirror image thereof;

FIG. 6 is a perspective view of the box for a book of FIG. 1; and,

FIG. 7 is a plan view of the box for a book of FIG. 1 in unfolded condition.

The dashed lines in FIG. 7 are understood to represent fold lines.
